UNITED STATES PATENT OFFICE

ALFRED C. KORTE, OF ST. LOUIS, MISSOURI, ASSIGNOR TO METALCRAFT CORPORATION, OF ST. LOUIS, MISSOURI, A CORPORATION OF MISSOURI

DESIGN FOR A COASTER WAGON OR LIKE ARTICLES

Application filed February 27, 1933. Serial No. 47,325. Term of patent 7 years.

To all whom it may concern:

Be it known that I, ALFRED C. KORTE, a citizen of the United States, residing at St. Louis, in the State of Missouri, have invented a new, original, and ornamental Design for a Coaster Wagon or Like Articles, of which the following is a specification, reference being had to the accompanying drawing, forming parts thereof.

Referring to the drawing:

Figure 1 is a front view of the wagon, taken from an elevated position, the tongue being removed so that the formation of the front end of the body and the front axle may be more clearly observed.

Figure 2 shows a plan view of the wagon.

Figure 3 is a perspective view showing the top, side, and rear of the wagon.

According to my design, every possible part of the wagon is stream lined. The front wheels are enclosed as completely as possible by the wheel guard so that the comparatively unattractive tires and wheels are concealed. The front axle is substantially oval in cross section to match the shape of the wheel guard. The headlight is located in the central foremost portion of the body and the glass lens of the headlight which is surrounded by a nickel-plated retaining ring has the appearance of a medallion for decorative purposes, and the extempore appearance of the ordinary attached headlight is entirely avoided.

The rear wheel guards are similar in shape

to the front guards except that they are built into the body of the wagon in such a way that the curvature of the outer surface of the body flows smoothly into the curvature of the wheel guard. The body of the wagon is tapered off at the rear end as well as being tapered downwardly and outwardly all around the body, and the surface of the body extends down to substantially the level of the concealed rear axle, so that the comparatively unattractive running gear of the vehicle will be concealed.

The sides of the wagon bed are of substantial thickness, especially at the base, from which they are tapered inwardly and upwardly to a curved upper edge.

The wagon tongue is formed in substantially the same shape at both ends, except for the necessary bearing portion for attaching the same to the front axle. Each end of the tongue is enlarged transversely and provided with a large opening in the enlarged portion. Longitudinal corrugations are provided in the tongue for decorative purposes.

The wheel guards are provided with medallions centrally located with respect to the wheels.

I claim:

The ornamental design for a coaster wagon or like articles, substantially as shown and described.

Signed at St. Louis, in the State of Missouri this 24th day of Feb., 1933.

ALFRED C. KORTE.
